UNITED STATES PATENT OFFICE

VICTOR JOHN ENGLISH, OF VERDUN, QUEBEC, CANADA

COMPARTMENT GUARD

Application filed October 25, 1930. Serial No. 491,188.

The invention relates to a compartment guard, as described in the present specification and illustrated in the accompanying drawing that forms part of the same.

5 The invention consists essentially in the novel means employed of guarding the entrance to a wicket or serving counter of a compartment, such as a teller's cage, as more particularly pointed out in the claim for novelty 10 following a description in detail of the preferable construction.

The objects of the invention are to safeguard the officer in charge of funds or other valuables in banks, trust companies, jewellers 15 and other business or amusement houses where considerable sums of money are in danger through the operations of bandits; to incarcerate the bandit attempting the robbery in a very simple and effective manner 20 and securely hold him for delivery to the police; to furnish to banks and other institutions and corporations an efficient means of keeping the teller or other officer in direct communication with a single customer or 25 client at any one time and thereby save confusion and loss to both the institution and the teller through overcrowding at his wicket and at the same time facilitate the passage 30 of customers in regular order before the wicket without in any way delaying or inconveniencing the public; to insure the transaction of confidential business in all dealings that the institution officer may have with the person directly in front of him; and generally 35 to provide a novel means of dealing with the customers from a serving counter or wicket that will insure secrecy in the ordinary course of business dealings and that will also insure safety for the valuables placed in the 40 charge of the officer as well as saving the life of the officer in charge during any attack by a bandit.

In the drawing, Figure 1 is a perspective view showing a compartment and the guarded entrance to the wicket.

Figure 2 is a sectional plan view of the compartment illustrated in Figure 1.

Figure 3 is a vertical elevational view of the compartment through the guarded entrance.

50 Figure 4 is a detail of the door locking mechanism beneath the compartment entrance.

Figure 5 is a fragmentary view showing the locking connection to the back door of the 55 compartment.

Figure 6 illustrates fragmentary details of the back door lock.

Figure 7 is a plan view of the door locking mechanism illustrated in Figures 3 and 4. 60

Like numerals of reference indicate corresponding parts in the various figures.

Referring to the drawing, the compartment, indicated by the numeral 15 is formed with a wicket 16, recessed inwardly from the 65 front wall and situated immediately above the serving counter 17.

The arcuate walls 18 and 19 extend outwardly from within the recess 20 and on one side 21 the arcuate wall extends outwardly 70 to a greater extent than on the other side 22, so that the entrance is plainly shown.

These arcuate walls 18 and 19 close in above and below the wicket portion, so as to practically form an inward extension of the front 75 wall 23 of the compartment, and at the same time form an entrance to the wicket 16.

The revolving door 24 is formed of the two hollow sections or wings 25 and 26, which converge from the arcuate walls 27 and 28 to 80 the operating shaft 29 to which the said sections 25 and 26 are fixedly secured.

The upper end of the shaft is journalled above the roof 30 of the door in the door frame 31 and at the lower end in the door 85 frame 31, the bearings for this shaft providing smoothly running surfaces which may or may not be in the form of ball bearings.

The lower end of the shaft beneath the 90 flooring 32 carries the ratchet 33, which is

enclosed in the fixed casing 34 from which the lug 35 extends.

The pawl 36 is pivotally secured to the lug 35 and engages the teeth 37 of the ratchet 33 slipping from one to the other of said teeth and holding said door from reversal.

The stops 38 project from the ratchet 33 at intervals preferably at quarter intervals and turn with said ratchet within the casing 34.

10 The locking lever 39 is pivotally secured to the bracket 40 screwed to the compartment floor 41 and the pedal 42 of said lever extends through the flooring 41 and into the compartment below the serving counter and 15 is convenient for foot operation.

The lever 39 carries at its inner end a locking bolt 43 which normally occupies a neutral position so that the ratchet is free to turn without hindrance of any kind.

20 The pressure on the pedal 42 brings the locking bolt between stops and the door is free to turn and just as soon as the door has reached the extremity, that is to say, up to the stop, a further pressure on the pedal locks 25 the door from movement in either direction, as the locking bolt, which is of the split variety reaches into the slots 44 in the stops, thus any person entering by means of this rotary door pushes the sections around until the person 30 becomes enclosed in a closet 45 before the serving counter, and presuming this person to be a bandit, he immediately points his gun at the officer behind the counter through the wicket and makes him deliver all the money 35 within his charge, which the officer makes no objection to. However, immediately the bandit starts away with his loot, the officer presses down on the pedal and maintains the pressure with his foot until the locking bolt 40 reaches a stop 38 and particularly the slots 44 and then the closet 45 is changed, so that in place of the open wicket before the bandit, there is a blank wall, and he is unable to move the door one way or the other, for the door 45 cannot be reversed in any case, but on the other hand, it is doubly locked and can only be opened by the release of the locking bolt, which can certainly be held in place until the police arrive on the scene.

50 It is also important for the rear door to be locked while the teller is serving at the counter, and to do this the shaft 29 is connected by the belt and pulley mechanism 46 with the locking bolt 47 mounted on the slotted shaft 55 48 turning in the correspondingly slotted sleeve 49.

The slotted shaft operates coincidently with the operating shaft 29 and keeps turning the locking bolt 47 into open and shut positions, that is to say, across and in alignment with the slotted sleeve 49, so that in each open position, that is to say, when the closet 45 is opposite the wicket the teller or other officer is presumably facing his customer with his back to the back door, and

in this position the back door is locked, but in the position where the door sections bar off the wicket, then the back door is open and the locking bolt 47 is in alignment with the slotted sleeve 49. There is of course another lock for the back door and the lock described may be opened by a responsible party or by the teller himself.

The armor plates 50 are secured on the walls of the compartment above and below 75 the counters and shelves so that the teller or other officer cannot be reached from a distance by a firearm, as these armor plates can be of sufficient thickness to stop the bullet of the ordinary firearm.

80 The operation has been fairly well described in explaining the details of the invention, but it will be readily seen that this entrance door to the wicket of the teller or other officer, offers no obstruction at all even for very crowded banks and trust companies, where long lines of persons are continually urging their way to the front of the teller's wicket, so much so that two or three 85 customers behind the one being served have full knowledge of the business being transacted at the time and there is no necessity for this because with this compartment guard, only one person can reach the teller at a time and yet there is no delay in the next 90 person's arrival in front of the teller.

95 It is exactly the same so far as time is concerned because they just keep moving along, each one arriving before the teller in the proper turn and the line of waiting customers 100 remains exactly the same as it is under existing conditions, but presuming that bandits enter a financial institution with the object of robbing the teller, the usual procedure of these bandits is to stand in front of the teller's wicket and in a low voice order him to push all his money towards the wicket and keep his hands up except for that one purpose, this of course has been constantly done 105 and many banks have been robbed of thousands of dollars and besides this, bank officers have been injured and killed in trying to defend money placed in their charge, but in this particular compartment guard, the bandit certainly can reach the front of the wicket just the same as any other customer and he can make the teller stand and deliver, but once the wicket is closed from view, he can do nothing and he has to get out, therefore when the gun is turned away from the teller, he is hidden by a blank wall. The bandit is of course incarcerated and held for the police, which is in the beginning the main object of this invention, though the other 120 objects are almost as important, that is to say, to prevent crowding at the teller's wicket in banks, particularly on certain days in the week when there are many outpayments to make.

What I claim is:—

A revolving door and arcuate wall enclosures extending outwardly from a counter, said door having diametrically opposite open compartments in one position and diametrically opposite close compartments in all positions, said open compartments forming close compartments with said arcuate walls during the operations of the door and means for operating said door from a distance and locking it.

Signed at Montreal, Canada, this 13th day of October, 1930.

VICTOR JOHN ENGLISH.
